UNITED STATES PATENT OFFICE.

OSCAR F. FALK, OF BELLEVILLE, NEW JERSEY, ASSIGNOR TO NATIONAL DICTOGRAPH COMPANY, A CORPORATION OF MAINE.

TELEPHONE DICTATING MACHINE OR APPARATUS.

967,748.

Specification of Letters Patent. Patented Aug. 16, 1910.

Application filed July 13, 1909. Serial No. 507,320.

To all whom it may concern:

Be it known that I, OSCAR F. FALK, a citizen of the United States, residing at Belleville, in the county of Essex and State of New Jersey, have invented certain new and useful Improvements in Telephone Dictating Machines or Apparatus, of which the following is a full, clear, and exact description.

- 10 This invention relates to a class of apparatus employed for dictating telephonically from a central office desk or station, selectively to any one of a corps of stenographers. Apparatus of this class forms the subject of prior Patents Nos. 843,186 and 880,537 and which embody telephone instruments connected by circuits of such a character that the particular or special purposes of dictation are served.
- 20 The present invention consists of a dictograph apparatus having all the essential functions of the prior apparatus above referred to, but in which the construction is much more simple, and better adapted for 25 the purposes of manufacture and practical use.

Prominent among the features of the present invention is the characteristic of accessibility of the various component parts or elements, and easy removability and interchangeability of such parts.

Another feature of the invention relates to means for making all the electrical connections without the use of complicated circuit wiring.

A third object of the invention is to provide what I term a supplemental frame for the support of the operating keys or jacks and their connections, whereby the latter 40 can not only be removed, but are always in condition to be inspected from any side or direction.

With the foregoing and other objects in view my invention consists in the features of 45 construction and combination as hereinafter set forth and claimed.

In the drawings: Figure 1 is a front elevation of a dictograph apparatus embodying the principles of my invention. Fig. 2 is a view of the same with the front of the casing removed. Fig. 3 is a top view with the top of the casing removed. Fig. 4 is a generally similar view except that the side walls of the casing are also removed and the parts 55 shown in a different position. Fig. 5 is a

sectional view on the line IV—IV of Fig. 4; and Fig. 6 is a detail view showing the manner in which the electrical connections are made between different keys.

Referring to the drawings in which like parts are designated by the same reference sign, 1 denotes a box or casing of rectangular outline and 2 indicates what I shall term a supplemental or skeleton frame and which I make in the form of an elongated square prism, preferably of metal running only along the corners or outlines thereof. Each of the faces of such supplemental prismatic frame constitute a base on which devices may be secured or mounted, extending between the side or edge bars thereof. Any device or object mounted in this manner is accessible from all sides or directions through the various open faces of this prismatic frame.

3 denotes operating keys which are combined with visual signals 4 which may be considered as permanently assembled together for the purposes of the present application. Each such combined signal and key 80 has a flat front plate 5 which is secured at 6 to the edges of the front face of the prismatic frame 2. Under these circumstances, the signals and keys extend back into the body or interior of said prismatic frame. 85

7 denotes the protruding spring blades of the key 3 and which project beyond the rear side or face of the prismatic frame 2.

8 designates an insulating bar preferably of hard wood which is fastened to extend 90 along the lower part of the rear side of the prismatic frame 2. The rear face of this bar 8 has a series of grooves 9 therein which are quite narrow and deeply recessed into the material of the strip.

10 denote metallic strips or ribbons located in the grooves 9 and extending along the length of the wooden bar. These ribbons constitute what may be termed bus-bars and have an important function in establishing the circuits of the key. For this purpose the insulating bar 8 has a hole or perforation 12 opposite each of the keys 3, and through which perforation the blades 7 protrude. The blades of the key are initially 105 bent by a forming die or fixture so that they fall automatically into registry with one of the bus-bars 10.

I have illustrated the connection of the spring blades with the bus-bars at 13. The 110

particular features of this engagement constitute more particularly the subject of my companion application Serial No. 508,971 filed herewith and are claimed therein. I

5 shall not therefore set forth the features of this construction in greater detail in the present case.

15 denotes a swinging instrument frame pivoted on the skeleton or prismatic frame 2 at the point 16 so as to swing in a horizontal plane corresponding to the top face of the prismatic frame 2. The swinging frame 15 preferably comprises an integral sheet metal stamping of h-shaped outline with a prong

15 17 struck up on the small end or extremity.

19 denotes a U-shaped spring tongue or clip adjacent to the prong 17 and adapted to coöperate therewith to engage a flat or disk receiver 20 of sensitive type.

20 21 indicates a curved horn extending from the receiver 20 and terminating in an enlarged orifice 22 in a plane at right-angles to the plane of the receiver 20.

24 designates a U-shaped spring tongue or 25 clip fixed to the swinging frame 15 in a plane parallel with that of the orifice 22. This spring tongue 24 is adapted to receive a transmitter 25 having a mouthpiece 26, with its inlet orifice in the plane of the ori-

30 fice 22 of the horn 21. This plane is so related to the pivot point 16 of the swinging frame 15 as to swing into coincidence with the front face of the skeleton frame 2 at a certain position of said swinging frame.

35 This position corresponds to a coincidence of the prong 17 with a side face of the skeleton frame 2. The casing 1 is designed to fit the outline of the skeleton frame 2 closely on its front and side faces, thereby insuring

40 that the transmitter and receiver orifices are pressed against the front wall of the casing on account of the engagement of the prong 17 with an interior side wall of the casing.

28 and 29 denote series of perforations 45 which I provide in the front face of the casing opposite the orifice of the transmitter and receiver horn respectively.

30 denotes a buzzer also fixed to the swinging frame 15 and having its circuit connections included in a series circuit with a pair 50 of spring blades 31 on a forwardly projecting part of the swinging frame 15, whereby they are located closely adjacent to the front wall of the casing 1 in normal use as clearly 55 shown in Fig. 3. In the wall of the casing at this point I provide a turn-button 33 with a cam 34 adapted to bear downward on the upper spring blade 31 thereby establishing a contact.

60 The various electrical circuits are established by flexible connections from the receiver 20 and the transmitter 25 to the bus-bars 10. All of the remaining electrical connections are established by the engagement 65 of the key blades with the bus-bars; these

circuits and features being set forth in detail in my companion application above referred to, will not require repetition in this case.

What I claim, is:—

7 1. In a telephone system or apparatus, a manager's instrument having a casing, a prismatic skeleton frame contained therein, keys and signals supported by said frame, a swinging frame pivoted to said supplemental frame, and a transmitter and receiver fixed to said swinging frame.

71 2. In a telephone system or apparatus, a manager's instrument comprising a casing, a supplemental skeleton prismatic frame 80 adapted to fit within said casing, keys and signals supported by said supplemental frame, a swinging frame, a transmitter and a receiver supported thereby, and means for fixing the position of said swinging frame 85 by the engagement thereof with the box or casing.

3. In a telephone system or apparatus, a manager's station comprising a skeleton supplemental prismatic frame, combined keys 90 and signals supported by the front face of said frame and extending into the frame, a swinging frame pivoted to the top face of said supplemental frame, and a transmitter and a receiver fixed to said swinging frame. 95

4. In a telephone system or apparatus, a manager's station comprising a box or casing, a supplemental skeleton prismatic frame adapted to fit within the lower front part of said box or casing, keys and signals supported by said supplemental frame, a swinging frame pivoted to the top of said supplemental frame, and a transmitter and a receiver fixed to said swinging frame. 100

5. In a telephone system or apparatus, a manager's station comprising a box or casing, a supplemental skeleton prismatic frame adapted to fit within the lower front part of said box or casing, keys and signals supported by said supplemental frame, a swinging frame pivoted to the top of said supplemental frame, and a transmitter and a receiver fixed to said swinging frame, the position of said swinging frame being fixed within said box or casing by its engagement 115 therewith to properly locate said transmitter and said receiver.

6. In a telephone system or apparatus, a manager's instrument comprising a box or casing, an interior supplemental skeleton 120 frame, keys and signals supported by said frame, a swinging h-shaped frame pivoted to the top of said supplemental frame and having a prong at one end, and a transmitter and a receiver supported by said 125 swinging frame, said prong engaging a wall of said casing to properly locate said transmitter and receiver therein.

7. In a telephone system or apparatus, a manager's instrument comprising a box or 130

casing, a supplemental skeleton prismatic frame contained therein, keys and signals supported by said supplemental frame, a swinging frame on said supplemental frame, 5 a transmitter and a receiver, and means for removably supporting said transmitter and receiver on said swinging frame.

8. In a telephone system or apparatus, a manager's instrument comprising a box or 10 casing, a supplemental skeleton prismatic frame contained therein, keys and signals supported by said supplemental frame, a swinging frame on said supplemental frame, a transmitter and a receiver, and spring 15 clips for removably supporting said transmitter and receiver on said swinging frame.

9. In a telephone system or apparatus, a manager's instrument comprising a skeleton prismatic frame having keys and signals 20 supported therein, an insulating bar extending across the back of said frame and having perforations through which the blades and keys project, and bus-bars supported by said insulating bar and extending across the 25 perforations thereof in positions adapted to be engaged by the key blades.

10. In a telephone system or apparatus, a manager's instrument comprising a skeleton frame; keys and signals therein, an insulating bar extending across the back of said 30 frame and having deep narrow grooves and further having perforations through which the blades of the keys extend, and metallic ribbons or bus-bars contained in said grooves and adapted to be engaged by the key 35 blades.

11. In a telephone system or apparatus, a manager's instrument comprising a frame, keys and signals therein, an insulating bar extending across the back of said frame and 40 having grooves, metallic ribbons or bus-bars in said grooves adapted to be engaged by the key blades, a transmitter and a receiver removably attached to said frame, and flexible connections for said transmitter and 45 said receiver.

In witness whereof, I subscribe my signature, in the presence of two witnesses.

OSCAR F. FALK.
